UNITED STATES PATENT OFFICE.

ELMER L. SCHUMACHER, OF SOUTHBIDGE, MASSACHUSETTS, ASSIGNEE TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,341,344.

specification of Letters Patent. Patented May 25, 1920.

Application filed November 30, 1917. Serial No. 204,596

To all whom it may concern:

Be it known that I, ELMER L. SCHUMACHER, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to a novel and improved construction of frame of what is commonly known as the Windsor type; that is to say, a frame having certain metallic and certain non-metallic portions.

One of the leading objects of the present invention is the provision of novel and improved means for readily and securely connecting the metallic and non-metallic portions of the mounting.

A further object of the invention is the provision of connecting means which shall be quite ornamental in appearance when the mounting is viewed on the face of the wearer and which will securely retain the parts together.

A further object of the invention is the provision of novel and improved means for detachably connecting the ends of the non-metallic frame member to the remainder of the mounting so that said frame member may be readily removed or replaced as desired.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front elevation of a mounting embodying my improvements.

Fig. II represents a fragmentary sectional view thereof.

Fig. III represents an enlarged perspective view of the construction shown in Fig. II.

Fig. IV represents a horizontal sectional view thereof.

Fig. V represents an enlarged fragmentary view of a modified construction.

Fig. VI shows a horizontal section thereof.

Fig. VII represents a vertical section thereof.

Fig. VIII represents a horizontal section of another modified form of my invention.

Fig. IX represents an enlarged view partially in section of the structure shown in Fig. VIII.

Fig. X represents a rear view of another modified form of my invention.

Fig. XI represents an end view thereof.

Fig. XII represents a view of a further modification in partially assembled form.

Fig. XIII represents an end view of the parts assembled.

Fig. XIV represents a fragmentary perspective view illustrating the formation of the end of the non-metallic frame member.

In the drawings I have shown a spectacle mounting comprising a bridge or center 1, and suitable frames at the ends of the bridge for retaining in position the lenses 2, these frames preferably comprising the inner metallic frame member 3 and outer non-metallic frame member 4, and employing the end piece members 5 to detachably connect the ends of the frame, said end piece members being held together as by the screws or fastening devices 6, one of which at each end piece also serves as a pivot for a temple member 7. It is to be understood, however, that while I have here illustrated and particularly described a spectacle form of construction, that my invention is equally applicable to eyeglasses or other desired types of mountings.

In that form of my invention shown in detail in Figs. II, III and IV, I have illustrated as secured to or integral with the frame 3 at one side the band 8 having at its free end the offset ear 9 adapted to be secured as by the screw 10 to the adjacent end piece member, in use the non-metallic frame being placed in position around the metallic frame and forced down tightly thereagainst, when the band 8 is bent and drawn around the end of the non-metallic frame member and secured by the screw 10, tightening of the screw 10 serving to draw the band around and clampingly secure it against the end of the frame member 4 so that the frame is securely held in place.

In Figs. V to VII inclusive, I have shown a modified form of my invention in which in place of the band 8 being secured at one end and free at the other, it is secured to

the metallic frame at both ends, but is of such size that the end of the non-metallic frame may be readily slipped inside the band, the non-metallic frame being preferably formed with a groove or channel 11 to receive the band.

After the parts have been assembled and to securely hold the band in place, I form on the end piece the offset 12 to form a seat for the taper screw 13 which is passed downward between the band and frame and as it is tightened serves to form an outward loop at the one side of the band and to tightly draw the remainder of the band around the non-metallic frame.

Figs. VIII and IX illustrate another form, in which the band 8 is fastened at the one end and is loose at the other, the loose end being adapted to be inserted in the slot 14 of the post 15, a screw driver being inserted in the slot above the band to turn the post, which may be locked in desired adjusted position by tightening of the nut 16, prongs 17 on the post interengaging with the end piece to aid in retaining the parts in position.

In Figs. X and XI, I have shown the band in place of extending entirely around the non-metallic frame member as formed in a substantially L-shape attached at one end to the frame and at the other end to the end piece member, being adapted to be sprung outwardly sufficiently to allow the end of the frame member 4 to be pressed or snapped therebeneath, when it will come back into tight engagement with the frame, preferably fitting within a suitable groove in the frame, and will suitably retain the frame in place, while being entirely invisible when the mounting is viewed from the front.

A slight variation of this construction is illustrated in Figs. XII and XIV, in that the member instead of being exactly L-shape is of angular formation and is provided at

the angle with an aperture adapted to receive a fastening screw 18 to most securely connect the parts, in this instance likewise the member being bent outward somewhat as indicated in Fig. XII, while the non-metallic frame is placed in position and then bent downward into the groove 19 and there secured through the use of the screw 18.

I claim:

1. The combination with a metallic frame, of a non-metallic frame extending therearound, bands on the metallic frame embracing the ends of the non-metallic frame, and means for tightening the bands for firmly securing the parts together.

2. In an ophthalmic mounting the combination with a metallic frame member, of a non-metallic frame member extending therearound, a band loosely secured to one of said frame members, and means for locking the band in engagement with the other frame member for securely uniting the parts.

3. In a device of the character described, the combination with a metallic frame, and a co-extensive non-metallic frame, of bands on the metallic frame embracing the ends of the non-metallic frame, and means for adjusting the tension of the bands.

4. In an ophthalmic mounting, the combination with a metallic frame member, of a flexible band loosely carried thereby, a non-metallic frame member engaging the metallic frame member, and means for securing the band in tight engagement with the non-metallic frame member to retain the latter in position.

In testimony whereof I have affixed my signature in presence of two witnesses.

ELMER L. SCHUMACHER.

Witnesses:

H. E. COLEMAN,
A. S. CANN.
